UNITED STATES PATENT OFFICE.

FRANK J. KOHLHAAS, OF CALUMET, MICHIGAN.

CURRENCY-HOLDER.

986,069.

Specification of Letters Patent.

Patented Mar. 7, 1911.

Application filed December 7, 1910. Serial No. 595,996.

To all whom it may concern:

Be it known that I, FRANK J. KOHLHAAS, a citizen of the United States, residing at Calumet, in the county of Houghton and 5 State of Michigan, have invented certain new and useful Improvements in Currency-Holders, of which the following is a specification, reference being had to the accompanying drawings.

10 This invention relates to improvements in filing devices and particularly to improvements in devices having for their purpose to file and hold currency in banks; and an object of this invention is to provide a device 15 which will enable currency in bank-cages to be handled conveniently and expeditiously.

Another object of this invention is to provide a device by means of which the currency may be kept as compactly as possible 20 within the limited space available in bank-cages and bank-vaults.

A third object of this invention is to provide a device by means of which the currency will be securely held and be protected 25 from being torn or wrinkled.

In the drawings illustrating the principle 30 of this invention and the best mode now known to me of applying that principle, Figure 1 is a plan view of my new currency holder; Fig. 2 is a side elevation of the same; Fig. 3 is a section on the line A—A of Fig. 2 and Fig. 4 is a detail which shows the follower-plate in holding position.

The frame *a* of the device is made by 35 bending a steel rod into U-shape and then turning up the ends *b* of the side-bars *c*. To these ends *b* is fastened an abutment-plate *d* which is inclined toward the base *e* of the frame, the inclination being about ten degrees from the vertical, as is best shown in 40 Fig. 2. Mounted slidably upon the side-bars *c* of the frame *a* is a follower-plate *f* which is provided with a pair of legs *g*, the lower or base ends of which are formed with 45 holes *h*. The axes of the holes *h* are inclined at an angle of about ten degrees to the axes of the side-bars *c*, which pass through these holes. From this construction it results that the follower-plate *f* is mounted free to tilt 50 on the side-bars *c*. When the follower-plate is thrown toward the abutment-plate *d* (see dotted lines in Fig. 2) the follower-plate is released so that it may be slid along the side-bars *c* toward or from the abutment-plate *d*. 55 When the follower-plate is in holding position (that is, thrown away from the abut-

ment-plate), it is still inclined to the latter, the distance between the bases of these plates being then greater than the distance between their upper edges. This is an important 60 feature of my invention, since it insures that the currency will be firmly held in a sort of wedge-shaped mass (Fig. 2). To the follower-plate *f* is fastened a card holder *i* in which a card *j* may be placed having written 65 upon it the name of the teller and the amount of the bundle of currency held between the plates *f*, *d*. The base *e* of the frame serves as a bail or handle by which the device may be rapidly handled and conveniently carried. 70

Due to the inclination of the plates *f*, *d* there is no danger of the currency's falling out, while the latter is being carried in the device from the bank-vault to the teller's 75 cage. The device permits of storing a greater amount of currency in a bank-vault than can otherwise be done safely and conveniently. The device itself occupies very little space, is simple in construction, comparatively cheap in manufacture and efficient in use. If it be desired, the base *e* may be used as means for hanging the device from overhead or upon the wall, whereby economy of space may still further be obtained. 80

The side-bars *c* and the base ends of the legs *g* are made of hardened steel to withstand the wear to which these parts are in use subjected. 90

I claim:

1. A device of the character described consisting of a U-shaped frame having side-bars; an abutment-plate which is fastened to the ends of the latter; and a follower-plate having a pair of legs formed with holes the axes of which are inclined to the axes of said side-bars, which side-bars pass through said holes, whereby said follower-plate is mounted slidably and free to tilt 100 upon said side-bars; said abutment-plate and follower-plate being in holding position inclined toward each other, whereby the distance between the bases of said plates in holding position is greater than the distance 105 between their upper edges.

2. A device of the character described consisting of a frame formed of a rod bent into U-shape; an abutment-plate which is fastened to the ends of said rod and which is 110 inclined toward the base end of said frame; and a follower-plate having a pair of legs

formed with holes the axes of which are inclined to the sides of said U-shaped frame, which sides pass through said holes, whereby said follower-plate is mounted slidably and free to tilt upon said sides; said plates being in holding position inclined toward each other, whereby the distance between the bases of the same in holding position is greater than the distance between their upper edges; the base end of said U-shaped

frame serving as a bail or handle by which to carry the device.

In witness whereof I hereunto set my hand at Calumet, Michigan, this third day of December, 1910, in the presence of the 15 two undersigned witnesses.

FRANK J. KOHLHAAS.
